UNITED STATES PATENT OFFICE.

JOHN G. PETTIS, OF CHICAGO, ILLINOIS, ASSIGNOR TO THE IMPERIAL BRASS MANUFACTURING COMPANY, OF CHICAGO, ILLINOIS, A CORPORATION OF ILLINOIS.

MIXING-HEAD FOR GAS-TORCHES.

1,172,729.

Specification of Letters Patent. Patented Feb. 22, 1916.

Application filed December 14, 1914. Serial No. 877,042.

To all whom it may concern:

Be it known that I, JOHN G. PETTIS, a citizen of the United States, residing at Chicago, in the county of Cook and State 5 of Illinois, have invented new and useful Improvements in Mixing-Heads for Gas-Torches, of which the following is a full, clear, and exact description.

My invention relates to gas torches for 10 welding and cutting metal, and particularly to torches of this character employing means for producing both a combined acetylene and oxygen gas, and supplying a pure oxygen gas under pressure.

15 The object of my invention is to provide valve-controlled means for dividing and utilizing the oxygen gas obtained from one of the valve-controlled systems of passages through the torch without affecting the necessary supply of oxygen to mix with acetylene gas that flows through the other system of passages therethrough, and a further object of my invention is to provide both a manually operated and automatically operated valve-control for such divided stream 20 of pure oxygen gas.

These and other objects I am enabled to accomplish by the means hereinafter fully described, and as particularly pointed out 30 in the claims.

In the drawings: Figure 1 is a longitudinal section of a gas torch embodying my improvements that has part of the pipes leading therefrom to the tip broken away. 35 Fig. 2 is a transverse section therethrough taken on dotted line 2-2, Fig. 1. Fig. 3 is a transverse section taken on dotted line 3-3, Fig. 1. Fig. 4 is a transverse section taken on dotted line 4-4, Fig. 1. Fig. 5 is a transverse section taken on dotted line 40 5-5, Fig. 1.

45 Referring to the drawings, A represents a handle consisting of a tubular casing of sufficient length which is closed by a suitable plug a at its rear end and by a suitable body B at its forward end. This body projects forward beyond said handle a suitable distance, and has the reduced rear screw-threaded end of an axially alining 50 mixing-head C screwed into the same. This mixing-head has a central bore c therethrough and has a spiral groove c' extend-

ing from the rear end of its exterior to the tapered forward end thereof, and it is inclosed within the correspondingly shaped 55 rear end portion of the bore of a pipe D.

The rear end of pipe D is exteriorly threaded and screwed into the countersunk forward end of body B concentric with the mixing-head, and a gland-nut d is screwed 60 onto this rear end the annular flange of the bell-shaped rear end of which incloses the forward end of the body. The rear edge of pipe D is beveled inwardly or countersunk and provides an annular chamber d' 65 around the rear end of the mixing-head from which the oxygen gas is fed to the spiral groove c', and discharged therefrom into and mixed with the acetylene gas discharged into the bore of pipe D, which 70 latter conveys the said gaseous mixture into a tip X. The construction of this tip forms the subject-matter of a co-pending application filed December 14, 1914, Serial No. 877,043, and, therefore, is not described 75 herein.

The tubular casing of the handle has two longitudinally disposed pipes e and f, extending therethrough, the rear ends of which extend into the plug a and are connected by suitable nipples with suitable gas supply sources (not shown). The forward ends of supply-pipes e and f are tapped into the rear end of body B, and are, respectively, connected by suitable valve connected passages to the bore of the mixing-head and the annular chamber d' at the rear of the same. The pipe e, from which the acetylene gas is obtained, discharges into a longitudinal bore 2 that extends forward a short distance into the bushing and empties into the transverse seat 3 of a spindle-valve 4. The conical shaped inner end of valve-seat 3 extends to or slightly past the axial center of the body, and connects with a transaxial passage 5 at right angles thereto, and this transaxial passage 5 has its outer end closed and its inner end communicating with a longitudinal passage 6, whose rear end is plugged up and whose 100 forward end discharges into a lateral passage 7 with which the rear end of the bore of the mixing-head communicates.

The pipe f, from which the oxygen gas

is obtained, discharges into a longitudinal passage 8 in the body that extends from the rear end to a point mediate transaxial passages 5 and 7, at which point it communicates with a lateral passage 9 which discharges into the valve-seat 10 of a spindle valve 12, whose axis is parallel to the axis of spindle-valve 4. A longitudinal passage 13 connects valve-seat 10 with the annular-chamber d' , and thus supplies the oxygen gas to the spiral groove encircling the mixing-head D.

The axis of needle-valve 12 and the lateral passage 9 are transaxial to the axis of the body, and the bore for said passage and valve-seat extends through the side of the body opposite needle-valve 12, and is increased in diameter and screw-threaded to receive the screw-threaded stub 14 of a valve casing which latter has an automatic valve for controlling the pressure of the divided stream of pure oxygen gas that passes therethrough and is fed to the tip of the torch in conjunction with the mixed acetylene and oxygen gases that have been combined by the mixing-head, as hereinbefore explained. The axis of this valve casing is parallel to that of the body, and it comprises two cast metal sections and stub 14 projects laterally from the forward section 15 thereof. The bore of stub 14 constitutes a lateral passage 16 that extends into section 15 to about its center in alinement with the axis of lateral passage 9 of the body, and the inner end of passage 16 extends to the rear and discharges into the seat of a needle-valve 18 the axis of the shaft of which latter alines with the axis of the casing. The shaft of valve 18 is provided with a series of longitudinal grooves or corrugations, and when the valve is open the gas from passage 16 will flow through these corrugations into a large chamber 19 surrounding the rear end of the shaft of the valve. This rear end of the shaft of valve 18 is provided with a circular head of sufficient diameter that normally bears against diaphragm 20, which latter consists of a circular plate of thin flat metal or leather the margins of which are secured against the annular rear edge of section 15 of the casing by the rear section 21 of the same.

Rear section 21 consists of a substantially cylindrical metal casting which has a central bore therethrough the forward end of which is of such increased diameter as to enable it to be screwed over the rear end of forward section 15. The diameter of this forward portion of the bore of section 21 is reduced to the diameter of chamber 19, thus creating a shoulder between which and the annular rear edge of the forward section the margins of diaphragm 20 are clamped and securely confined when the said rear section is screwed home. The rear face of

the diaphragm 20 has a circular pressure-foot bearing against it, and this face is adapted to be engaged by the forward end of a tubular set-screw 22 which engages the reduced screw-threaded rear portion of the bore of section 21. Said pressure-foot has a plunger 23 secured thereto which extends axially and rearwardly through the bore of screw 22 and has on its rear end a suitable head 25 with which to manipulate it.

The forward end of section 15 of the valve casing is provided with a short axial bore 26 and a suitable nipple 27 is adapted to be screwed into the same until its rear end is separated a short distance from the rear end of said bore. This leaves a circular chamber which is connected by a longitudinal exit passage 28 with chamber 19, substantially as shown. The forward end of nipple 27 is exteriorly screw-threaded and the rear end of a pipe 29 is inserted and secured therein by means of a gland-nut 30 or in any other suitable manner, which pipe leads to the tip from which pure oxygen gas is discharged in conjunction with the combined oxygen and acetylene gases discharged into pipe D from the mixing-head C, as hereinbefore specified.

The operation of my invention is apparent:—The acetylene gas discharges from pipe e into bore 2 and from thence into the transverse valve-seat 3 where the volume of the flow of gas is controlled by spindle-valve 4. From the valve-seat the acetylene gas flows into the transaxial passage 5 and from the latter enters the longitudinal passage 6 and from thence into the lateral passage 7 and to the rear end of the bore of the mixing-head. The oxygen gas discharges from pipe f into longitudinal passage 8 and from the forward end of this passage into lateral passage 9 which discharges the gas into valve-seat 10 of spindle-valve 12 which latter controls the flow of gas into the longitudinal passage 13 leading to annular-chamber d' , from which oxygen gas enters the spiral groove of the mixing-head. The oxygen gas is given a whirling movement by the spiral groove as it discharges from the forward extremity of the mixing-head and it combines with the acetylene gas, and together therewith discharges through pipe D.

A portion of the oxygen gas from passage 8 of the body enters the lateral passage 16 of the forward section 15 of the valve casing, and is controlled by needle-valve 18 as it flows into chamber 19 therefrom from whence it discharges through passage 28 into the rear end of the bore 26 and flows into pipe 29 leading to the tip. The volume of the oxygen gas flowing into chamber 19 is controlled by manipulating either screw 22 so as to press the diaphragm 20 forward and move the point of the shaft of needle-valve 18 forward into its seat, or by pushing the

plunger 23 forward (which the operator does by pressing his thumb against head 25) so as to temporarily control the diaphragm and valve to limit the flow of gas.

5. What I claim as new is:

1. A gas torch comprising a body and a valve casing, said body having passages therethrough, valves controlling said passages, and a device for mixing the gas issuing therefrom, and said valve casing having a chamber, a diaphragm in said chamber, an inlet passage to said chamber, a valve connected to said diaphragm controlling said inlet passage, and an outlet passage from 15 said chamber.

2. A gas torch comprising a body and a valve casing, said body having passages therethrough, valves controlling said passages, and a device for mixing the gas issuing therefrom, and said valve casing having a chamber, a diaphragm in said chamber, axially extending means for regulating the movement of said diaphragm, an inlet passage to said chamber, a valve connected to 25 said diaphragm controlling said inlet passage, and an outlet passage from said chamber.

3. A gas torch comprising a body and a valve casing, said body having passages 30 therethrough, valves controlling said passages, and a device for mixing the gas issuing therefrom, and said valve casing having a chamber, a diaphragm in said chamber, a plunger attached to and extending axially 35 from said diaphragm, a tubular set-screw through which said plunger extends, an inlet passage to said chamber, a valve connected to said diaphragm controlling said inlet passage, and an outlet passage from said 40 chamber.

4. A gas torch comprising a body and a valve-casing, said body having two independent sets of gas passages therethrough, valves controlling said passages, a lateral 45 passage extending from one of said gas passages out through the side of said body, and a device for mixing the gas issuing from said body, and said valve-casing having a chamber, a diaphragm in said chamber, an inlet passage to said chamber, a valve connected to 50 said diaphragm and controlling said inlet passage, and an outlet passage leading from said chamber.

5. A gas torch comprising a body and a valve-casing, said body having two independent sets of gas passages therethrough, valves controlling said passages, a lateral passage extending from one of said gas 55 passages out through the side of said body, and a device for mixing the gas issuing from said body, and said valve-casing having a chamber, a diaphragm in said chamber, means for regulating the movement of 60 said diaphragm, an inlet passage to said chamber, a valve connected to said dia-

phragm and controlling said inlet passage, and an outlet passage leading from said chamber.

6. A gas torch comprising a body and a valve-casing, said body having two independent sets of gas passages therethrough, valves controlling said passages, a lateral passage extending from one of said gas passages out through the side of said body, and a device for mixing the gas issuing from 75 said body, and said valve-casing having a chamber, a diaphragm in said chamber, a plunger connected to said diaphragm, a tubular screw through which said plunger extends, means for regulating the movement 80 of said diaphragm, an inlet passage to said chamber, a valve connected to said diaphragm and controlling said inlet passage, and an outlet passage leading from said chamber.

7. A gas torch comprising a body and a valve-casing, said body having two independent sets of gas passages therethrough, valves controlling said passages, a lateral passage extending from one of said gas passages out through the side of said body, and a device for mixing the gas issuing therefrom, and said valve-casing having a chamber, a diaphragm in said chamber, a regulating plunger for said diaphragm, an inlet 90 passage to said chamber, a valve connected to said diaphragm and controlling said inlet passage, and an outlet passage leading from said chamber.

8. A gas torch comprising a body having 100 a plurality of gas passages, and a device for mixing the gas issuing therefrom, and an exterior valve-casing communicating therewith having an interior chamber having inlet and outlet passages, and an automatic 105 valve in said chamber controlling one of said passages.

9. A gas torch comprising a body having a plurality of gas passages, and a device for mixing the gas issuing therefrom, and an 110 exterior valve-casing having an interior chamber having inlet and outlet passages, and an automatic valve in said chamber controlling said inlet passage.

10. A gas torch comprising a body having 115 a plurality of gas passages, a device for mixing the gas issuing therefrom, and a valve-casing having an interior chamber having inlet and outlet passages, an automatic valve in said chamber controlling one of said 120 passages, and a regulating means for said valve.

11. A gas torch comprising a body having a plurality of gas passages, a device for mixing the gas issuing therefrom, and valve-casing having an interior chamber having inlet and outlet passages, a valve in said 125 chamber controlling one of said passages, and regulating means for said valve tapped into said casing.

12. A gas torch comprising a body having 130

a plurality of gas passages, a device for mixing the gas issuing therefrom, and a valve-casing having an interior chamber having inlet and outlet passages, a valve in .5 said chamber controlling one of said passages, and a regulating diaphragm for said valve in said chamber.

In witness whereof I have hereunto set my hand and seal this 4th day of December, 1914.

JOHN G. PETTIS.
